ATTORNEY.

UNITED STATES PATENT OFFICE.

WALTER H. FRANKLIN, OF MOUNT VERNON, WASHINGTON.

FUEL AND REFUSE CONTAINER.

1,411,336.

Specification of Letters Patent.

Patented Apr. 4, 1922.

Application filed March 2, 1921. Serial No. 449,062.

To all whom it may concern:

Be it known that WALTER H. FRANKLIN, citizen of the United States, residing at Mount Vernon, in the county of Skagit and State of Washington, has invented certain new and useful Improvements in Fuel and Refuse Containers, of which the following is a specification, reference being had to the accompanying drawings.

10 This invention relates to combined fuel and refuse buckets or containers and has for its object to provide a device of this character capable of receiving a quantity of fuel such as kindling wood and conveying the same to the desired place without dropping or depositing any portion thereof until it is so desired by the user.

Another object is to provide a device of this character having oppositely inclined 20 ends, one of said inclined ends extending laterally of the receptacle to facilitate the brushing of dirt, etc., into the receptacle, and the opposite end cooperating with the sides to provide a funnel for properly discharging matter from the container or bucket.

A still further object of the invention is to provide a device of this character wherein the kindling wood of lengths greater than 30 that of the bucket or container, may be properly supported by the container and conveyed to the desired place.

A still further object of the invention is to provide a device of this character including separable handles which do not interfere with the filling of the bucket.

With these and further objects in view, the invention consists in the improved construction and arrangement of parts to be 40 hereinafter more particularly described, fully claimed and illustrated in the accompanying drawings, in which:

Figure 1 is a top plane view of a combined fuel and refuse container constructed 45 in accordance with an embodiment of the invention.

Figure 2 is a side elevation.

Figure 3 is a section taken on the line 3-3 of Figure 1, and

50 Figure 4 is a detail view of the handle.

Referring to the drawings, 5 designates a bucket or container including ends 6 and 7 and sides 8. The end 6 is inclined upwardly to provide a relatively broad spout which 55 permits dirt and like matter to be brushed

into the container when the same is disposed in an inclined position. In this way, the device serves as a dust pan. The end 7 is inclined upwardly similar to the end 6. The side portions of said ends are extended upwardly to provide jaws 9 which cooperate with the sides 8 and the bottom of the container to form a spout or funnel whereby matter within the container may be readily discharged.

The upper portions 10 of each of the sides 8 extend beyond the edges of the ends 6 and 7, while the ends of said sides are beveled towards the edges of the ends 6 and 7. By this novel arrangement the sides do not interfere with matter being deposited or discharged from the receptacle over the said ends and at the same time the portions 10 serve as extensions so that kindling wood of lengths greater than that of the container 75 may be supported by the edges of the ends 6 and 7 and the portions 10 of the sides 8. To reinforce the sides the upper edges thereof are curled outwardly to provide beads 11, a pair of openings 12 being provided in each 80 side member closely adjacent the beads.

In connection with the container, a pair of handles are used, each handle consisting of a length of material 13 having its end portions extended toward each other to provide a substantial U shaped handle. The bight portion 14 of the handle is extended in annular relation to the end portions thereof to provide a hand grip, while the extremities of said end portions are formed into hooks 85 15 adapted to be disposed in the openings 12, the hooks being so arranged that the handles may be readily disengaged when desired. The bight portion of each handle is adapted to extend over and engage the bight portion of the opposite handle so as to permit the user to grasp both hand grips at the same time in order to convey the container. When the container is being filled, the handles may be shifted outwardly thereof so as 90 not to interfere with articles or matter being placed in the container.

From the foregoing it will be readily seen that this invention provides a novel device which is not only capable of receiving and conveying fuel of various kinds, but may also be used as a container to receive dirt, dust and like foreign matter. In addition to this the device includes a novel construction of handle which firmly grips the container 110

on both sides and may also be adjusted to permit articles of various sizes to be placed within the container.

What is claimed is:

- 5 A fuel and refuse container comprising a substantially rectangular body member, the ends of said body member being formed into outwardly projecting spouts, the sides of one

of said spouts being substantially in alignment with the sides of the body member, the 10 sides of the remaining spout being disposed in angular relation to said sides of the body member.

In testimony whereof I hereunto affix my signature.

WALTER H. FRANKLIN.
